DEVICE FOR STRETCHING SKINS

August Wilhelm Oskar Montag, Berlin-Kopenick,
Germany

Application July 27, 1933, Serial No. 682,473
In Germany January 20, 1933

10 Claims. (Cl. 149—21)

The present invention relates to an improved stretching device for skins or hides. The novel device permits an equal uni-directional stretching of the skin in all portions which is of particular importance in glove-making. The invention entirely eliminates the long lasting and inaccurate stretching of skins or hides by hand as now practiced. Stretching apparatus has been used, which, however, causes the skin to stretch to a larger degree on the outer than in the middle portions; the latter disadvantage is also eliminated by the present invention which for the reasons set forth is of great value in glove-making.

It is therefore one of the main objects of the present invention to provide an improved stretching device adapted to uniformly stretch all portions of the skin in a predetermined direction.

A further object is to provide a stretching device consisting of two stretching frames between which the skin is engaged.

Other objects and advantages of the invention will be seen from the following specification and the claims.

The novel device comprises two frames, each frame consisting of a plurality of pivotally connected bars; the frames are laid one above the other and the skin is inserted between the frames. Projections are provided on the pivots of the previously mentioned bars the projections of both frames being brought into register so as to engage the skin. If the frames are pressed each against the skin and if the bars are then moved about their pivots, the skin being firmly held between the frames will be stretched in one direction to the desired degree. The degree of stretching may be determined by means of a gauge.

A preferred embodiment of the invention is shown in the accompanying drawing:

Fig. 1 shows the upper frame;

Fig. 2 shows the lower frame with a skin;

Fig. 3 shows the position which the lower frame and the skin assume if the device is in stretching position.

Fig. 4 is an enlarged fragmentary view in perspective showing the intersection of two bars of the respectively parallel sets thereof in the upper frame.

Fig. 5 is a view in elevation showing the detailed construction of the pivot pin.

Fig. 6 is a view in elevation showing the pivot pin employed to pivotally connect the cross bars in the lower frame.

Fig. 7 shows the gauge for determining the stretching of the skin.

As will be seen from the drawing, the skin stretching device consists of two similar upper and lower frames 1 and 2; each frame consists

of two sets of parallel bars 3 and 4, the one set crossing the other one, and said bars are pivotally connected to each other at the crossing points. The middle bars 5 of each frame are stronger and serve as actuating bars for contracting and extending the frames for stretching the skins. The various bars of each frame are connected on the crossing points by screws 6, 6' in such a manner that they may easily pivot but cannot move relatively to their pivots. 10 The connecting screws of the various bars of the lower frame 2 form the pivots and are provided with a slightly rounded projecting head 7 which is roughened on the surface in order to firmly grip the skins and prevent the same from slipping. 15 When tender skins are to be stretched it is advisable to provide the screws 6 with a rounded rubber head in order to prevent any damage to the skin. The connecting screws 6' for the bars of the upper frame constitute the pivots 20 and are provided with a larger head 9 which is accurately bored out to form the seat for a rubber block 10 (Fig. 5) which normally is held in the seat of the head 9 so that upon lowering of the upper frame 1 upon the lower frame 2 the 25 skin will not be damaged due to the relatively heavy weight of said upper frame. In this connection it must be mentioned that the frames are sufficiently heavy so that no further clamping means are necessary when the upper frame 30 is resting upon the lower one.

It will be seen that on the pivots of the bars of the lower frame 1 the heads 7 of the bolts 6 form a support for the skin while the rubber blocks 10 of the bolts 6' of the upper frame engage the skin from the upper side thereof. 35

The actuating bars 5 of each frame are provided at each end with a hole 11 through which a pin (not shown) may be passed in order to hold the frames in register. It is, of course, 40 also possible to provide any other means serving the same purpose.

The gauge 12 (Figs. 7 and 8) used for securing the frames in stretching position and for determining the degree of stretching is provided with 45 slots 13 at both ends which act as guides in which slide the pins which pass through the ends of said actuating bars. The gauge 12 is also provided with holes 14 adapted to receive securing bolts or pins in order to secure the frames in the 50 adjusted stretching position. Of course, many variations may be made in these constructions.

Stretching of the skin is effected in the following manner: The skin is laid with the inner or flesh side upon the lower stretching frame 2; 55 the upper frame is then brought into register with the lower frame by means of pins which are passed through the holes 11 provided at the ends of the actuating bars 5 of the upper and lower frames. When the upper frame is in position 60

upon the lower frame, if desired or necessary, the upper frame can be loaded by weights so that the skin is firmly held in engagement therebetween by the heads of the pivot screws of the various bars. The gauge is then placed upon the ends of the bars 5, the initial position noted, and both frames are then actuated slightly beyond the desired degree of stretch to eliminate any back-movement of the skin. The frames are then secured in their adjusted position by passing bolts through the desired holes 14 in the gauge so that the frames may be maintained in said adjusted position.

Due to the equal spacing of the connecting screws of the various bars and due to the firm clamping of the skin between the frames, the skin is forced to uniformly follow the slightest movements of the frames in exactly the same manner and thereby an absolutely equal unidirectional stretching of the skin in its smallest portions is obtained. Thus it will be seen that the unstretched skin in Fig. 2 can be stretched (see Fig. 3) in a longitudinal direction while, of course, the skin contracts transversely for a substantially equivalent amount within the limits of practical use of the invention.

Many modifications may, of course, be provided, without departing from the spirit of the invention.

What I claim is:

- 30 1. A device for stretching skins or hides in a predetermined direction, said device comprising two registering frames each consisting of a set of parallel bars and a second set of parallel bars crossing the bars of said first set, pivots connecting the bars in each of said sets to the bars in the other at the crossing points, and projections on said pivots in the adjacent faces of the frames to engage and firmly hold the skin therebetween.
- 40 2. A device for stretching skins or hides in a predetermined direction, said device comprising two registering frames each consisting of a set of parallel bars and a second set of parallel bars crossing the bars of said first set, pivots connecting the bars in each of said sets to the bars in the other at the crossing points, projections on said pivots in the adjacent faces of the frames to engage and firmly hold the skin therebetween, and means for maintaining the frames in stretching position.
- 50 3. A device for stretching skins or hides, said device comprising two registering frames each consisting of a set of parallel bars and a second set of parallel bars crossing the bars of said first set, pivots connecting the bars in each of said sets to the bars of the other at the crossing points, the center bar in each of the sets of bars in the frames extending beyond said frames and constituting an actuating bar therefor, and projections on the pivots in the adjacent faces of the frames to engage and firmly hold the skin therebetween.
- 60 4. A device for stretching skins or hides, said device comprising two registering frames each consisting of a set of parallel bars and a second set of parallel bars crossing the bars of said first set, pivots connecting the bars in each of said sets to the bars of the other at the crossing points, the center bar in each of the sets of bars in the frames extending beyond said frames and constituting an actuating bar therefor, projections on the pivots in the adjacent faces of the frames

to engage and firmly hold the skin therebetween, and means for maintaining the frames in stretching position.

5. A device for stretching skins or hides, said device comprising two registering frames each consisting of a set of parallel bars and a second set of parallel bars crossing the bars of said first set, pivots connecting the bars in each of said sets to the bars of the other at the crossing points, the center bar in each of the sets of bars in the frames extending beyond said frames and constituting an actuating bar therefor, projections on the pivots in the adjacent faces of the frames to engage and firmly hold the skin therebetween, and means associated with said actuating bars 15 for determining the degree to which the skins are stretched.

6. A device for stretching skins or hides, said device comprising two registering frames each consisting of a set of parallel bars and a second set of parallel bars crossing the bars of said first set and pivotally connected thereto at the crossing points, one of said bars in each of said sets extending beyond the frame and constituting an actuating bar therefor.

7. A device for stretching skins or hides, said device comprising two registering frames each consisting of a set of parallel bars and a second set of parallel bars crossing the bars of said first set and pivotally connected thereto at the crossing points, one of the bars in each of said sets being of greater cross section area than the others and extending beyond the frames to constitute actuating bars therefor.

8. A device for stretching skins or hides, said device comprising two registering frames each consisting of a set of parallel bars and a second set of parallel bars crossing the bars of said first set and pivotally connected thereto at the crossing points, one of the bars in each of said sets being of greater cross section area than the others and extending beyond the frames constituting an actuating bar therefor, and means for maintaining the frames in stretching position.

9. A device for stretching skins or hides, said device comprising two registering frames each consisting of a set of parallel bars and a second set of parallel bars crossing the bars of said first set and pivotally connected thereto at the crossing points, one of the bars in each of said sets being of greater cross section area than the others and extending beyond the frame constituting an actuating bar therefor, and means associated with said actuating bars for determining the degree to which the skins are stretched.

10. A device for stretching skins or hides in a predetermined direction, said device comprising two registering frames each consisting of a set of parallel bars and a second set of parallel bars crossing the bars of said first set, pivots connecting the bars in each of said sets to the bars in the other set at the crossing points, projections on said pivots in the adjacent faces of the frames, and resilient means mounted in the projections of the pivots in one of said frames arranged to cooperate with the projections on the pivots of the other frame and engage and firmly hold the skin therebetween, the projection on the pivots in said other frame being rounded.
